US0D1104121S

(12) **United States Design Patent** (10) **Patent No.:** **US D1,104,121 S**
(45) **Date of Patent:** **** Dec. 2, 2025**

(54) **SUPPORT DEVICE FOR CAMERA**

(71) Applicant: **Shenzhen Leqi Innovation Co., Ltd.**, Shenzhen (CN)

(72) Inventors: **Zhiqiang Pan**, Shenzhen (CN); **Liang Guo**, Shenzhen (CN); **Fulin Pan**, Shenzhen (CN); **Jiaxin Mu**, Shenzhen (CN)

(73) Assignee: **SHENZHEN LEQI INNOVATION CO., LTD.**, Shenzhen (CN)

(**) Term: **15 Years**

(21) Appl. No.: **29/935,026**

(22) Filed: **Mar. 29, 2024**

(51) LOC (15) Cl. **16-05**

(52) U.S. Cl. **USPC .....** **D16/242**

(58) **Field of Classification Search**

USPC D16/237, 242-245; D14/251-253, 447
CPC G03B 17/56; G03B 17/561

(57) **CLAIM**

The ornamental design for a support device for camera as shown and described.

DESCRIPTION

FIG. 1 is a first perspective view of a support device for camera showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of encircled portion 9 of FIG. 1;

FIG. 10 is an enlarged view of encircled portion 10 of FIG.

1;

FIG. 11 is an enlarged view of encircled portion 11 of FIG.

2; and,

FIG. 12 is an enlarged view of encircled portion 12 of FIG.

2.

The broken lines depict portions of the article that form no part of the claimed design. In the FIGS. 1, 2, and 9-12, the dot-dash-dot broken lines encircling portions of the article that are illustrated in enlargements form no part of the claimed design.

1 Claim, 12 Drawing Sheets
